WILLIAM E. ZIEBER, OF YORK, PENNSYLVANIA, ASSIGNOR TO YORK ICE MACHINERY CORPORATION, OF YORK, PENNSYLVANIA, A CORPORATION OF DELAWARE

REFRIGERATION

Application filed October 10, 1929. Serial No. 398,745.

This invention relates to refrigeration and particularly to the automatic control of each one of a plurality of evaporators connected to the circuit, each evaporator being controlled independently of the other. The invention further includes in combination with the above recited features, the use of means to control the entire system by starting and stopping the compressor.

10 In a prior application Serial Number 299,271, filed August 13th, 1928, there is described a method of and apparatus for controlling flooded evaporators by regulating the suction connection so as to develop within the 15 evaporator a vapor pressure which at times displaces liquid refrigerant from the evaporator and thus controls its refrigerative effect.

The disclosure in said prior application is based on a system comprising a plurality of 20 ice cream freezers, to and from which volatile liquid refrigerant is admitted and discharged to control the freezing action. In ordinary 25 operation of ice cream freezers the control is to effect periodic suspension of the refrigerative action.

I have determined, however, that the principle disclosed and broadly claimed in said prior application can be used to effect progressive regulation of the refrigerative action. Briefly, it is possible to throttle the 30 suction connection and develop in the evaporator a variable vapor pressure which will result in the partial displacement of liquid refrigerant from the evaporator and a consequent reduction of the refrigerative effect.

The present application is limited to progressive regulation and is subordinate to the prior application above identified.

Another feature of the present invention is 0 the use of an evaporator gravity fed from a receptacle containing liquid refrigerant and maintained at suction pressure, the evaporator having two connections with the receptacle, one or both connections being below 5 the liquid level in the receptacle. One connection is constantly open and the other is valve-controlled. The receptacle may be a suction trap or a combined suction and liquid line connected with such a trap.

0 Two preferred embodiments of the inven-

tion are illustrated and described hereinafter, one of which is particularly adapted to installations where the evaporators are located on different floors of a building and consequently are at decidedly different levels.

These preferred embodiments of the invention are illustrated in the accompanying drawing, in which,—

Fig. 1 is a diagrammatic elevation of a refrigerative circuit showing four different types of evaporators connected to a single circuit and independently controlled, there being also an automatic control for the compressor associated with one evaporator.

Fig. 2 is a similar view showing a modification. In this modification the compressor control is omitted to simplify the drawing, but it may be used in the same form as that shown in Fig. 1.

In the drawing, 11 illustrates an ordinary compressor which is driven by means of an electric motor 12 through a belt 13. The high pressure connection 14 leads to a condenser 15 here illustrated as of the shell and tube water-cooled type, although any preferred condenser may be used. Refrigerant liquefied in the condenser 15 drains from the bottom of the condenser to a float trap 16. The trap 16 is provided with a float 17 which upon rise of liquid level in the trap casing opens the valve 18 to permit liquid refrigerant to flow to a combined liquid and vapor line 19. The line 19 is at least large enough to permit a partial separation of liquid and vapor, and to permit concurrent flow of the two streams of liquid and vapor to a separating trap or drum 21. This drum 21 is connected by the suction line 22 with the suction of the compressor 11. It follows that the liquid line 19 is maintained at suction pressure with the result that a portion of the liquid refrigerant immediately vaporizes, cooling the remainder. The line 19 and trap 21 in effect form a single volume maintained at suction pressure. While the line 19 is shown as entering the top of the trap 21 this is not essential.

In the arrangement illustrated, the line 19 tends to drain toward the trap 21, thus maintaining the upper portion of the line free

of liquid. The evaporators 23, 23^a and 23^b intercept and evaporate a considerable portion of the liquid, so that usually only a relatively small quantity flows to trap 21.

5 The horizontal portion of the pipe line 19 and the trap 21 form what is, in effect, a single receptacle maintained at suction pressure. The float trap 17 operates continually while the compressor is in operation, to deliver high pressure liquid refrigerant into low-pressure line 19. On admission part of this boils away cooling the rest to the temperature corresponding to suction pressure. There is thus at least a trickle of cold liquid 10 refrigerant flowing most of the time in the bottom of the horizontal run of pipe 19 toward trap 21.

As will be understood from details described hereinafter, this liquid flow is at 20 times supplemented by liquid refrigerant displaced from one or more evaporators by the regulatory action of their thermostatic valves.

At any rate there is, whenever the compressor is running, liquid refrigerant flowing 25 in the horizontal run of pipe 19, so that a liquid level is established in this pipe. The upper portion of the pipe 19 serves as a vapor passage.

30 Mounted below the line 19 so as to fill with liquid by gravity flow from the line 19 are the evaporators, three in number. For example, the coil 23 is an ordinary trombone coil. The connection 24 is preferably without 35 any controlling valves and the connection 25 is provided with a hand operated stop valve 26 for the purpose of shutting down the evaporator coil permanently, and with the thermostatically operated valve 27 performing the normal automatic regulation. This 40 valve is actuated by a thermostatic unit 28 preferably of the progressively acting type so arranged that when the temperature in the chamber 29, within which the coil 23 is 45 mounted, rises the valve 27 will be gradually opened, and as the temperature falls, the valve 27 will be gradually closed. The thermostatic element 28 thus acts to preserve in the chamber 29 a temperature which is regulated within relatively close limits.

50 In another chamber or space 31, there is shown an evaporator coil 23^a, with two connections to the line. The connections and valves associated with this coil are similar to those associated with the coil 23 and are similarly numbered with the subscript *a*. Coil 23^a is submerged in water in a tank 32 and functions to cool that water. In order to secure a proper regulation of the water temperature the thermostatic element 28^a is submerged in the water in the tank 32.

55 In a third chamber 33 is a third coil 23^b having connections and valves functionally similar to those associated with the coil 23, but differently arranged. The coil 23^b, forms

the part of a brine cooler of the double pipe type, and the sinuous chamber 34 forms a passage for brine which surrounds the coil 23^b. In order to regulate the valve 27^b in response to the temperature of the off-flowing brine, the thermostatic element 28^b is indicated as closely associated with the lower end of the sinuous chamber 34 so as to respond to the brine temperature. There is also a slight change in the connections, the pipe 24^b serving as a combined liquid and vapor line, that is an extension of line 19 to which the coil 23^b has two connections, one (the lower) constantly open and the other controlled by valves 26^b and 27^b. This arrangement is 70 equivalent to and interchangeable with that previously described.

75 The evaporators might be multiplied almost indefinitely and might be of the same or different types. It is not essential that any evaporator be connected directly to the trap 21, but it is conveniently possible to connect an evaporator to this trap and to illustrate that possibility I show a fourth evaporator 23^c which is enclosed in a separate cold room 80 or space 35. The connection 24^c which is the liquid connection leads from the bottom of the trap 21, and the connection 25^c leads, preferably, but not necessarily, to the top of the trap 21. The stop valve 26^c and the regulating valve 27^c, with its thermostatic control element 28^c, are similar in form and functions to the similarly numbered parts associated with the coil 23.

85 The trap 21 in the ordinary operation of the device will serve to accumulate a considerable quantity of liquid refrigerant, and for this reason it is desirable that the coil 23^c be the one which carries the heaviest and most sustained refrigerative load.

90 On this assumption, there is shown in the chamber 35 a thermostatic controller 36 which is connected by the wires 37 with an electrically actuated motor controlling switch 38. No attempt has been made to illustrate in detail 100 the thermostatic switch 36 or the motor controlling switch 38, but I contemplate using mechanism well known in the art and provided with those safety devices which are in current use. As the addition of these features involves nothing novel, and as the present invention is not directly concerned with their use, it has been deemed unnecessary to illustrate and describe them in detail.

105 It will be understood that the switch mechanism 38 controls the flow of motive current to the electric motor 12, so that the motor 12 is stopped and started in accordance with the action of the thermostatic switch 36. Since the chamber 35, and its evaporator 23^c have the heaviest and most sustained refrigerative load, it will normally happen that the thermostatically controlled valves 27, 27^a and 27^b will close before the thermostatically controlled valve 27^c closes. The switch 36 is so 115

adjusted that when, or shortly after, the thermostatic valve 27c closes, the thermostatic switch 36 will function to stop the motor 12, and will function to start the motor 12 at or about the time the valve 27c opens.

While it is convenient to treat the connections 24, 24a, etc. as the liquid connections, and the connections 25, 25a, etc. as the suction connections to and from the various evaporators 23, 23a and 23b, their functions are not necessarily absolutely distinct, for under some conditions vapor will rise through the connections 24, 24a, etc. However, the flow through the evaporators is generally in the direction implied by the designations given.

Assume, for example, that the thermostatic element 28 partially closes the valve 27. The vapor pressure in the corresponding evaporator 23 will rise somewhat and a portion of the liquid refrigerant will be displaced through the pipe 24 and will flow through the pipe 19, either to another evaporator or to the trap 21. Complete closure of the valve 27 will result in the displacement of all liquid refrigerant from the coil 23. The subsequent opening of the valve 27 will result in the entrance of liquid refrigerant into the coil 23, the amount of such refrigerant increasing as the valve opens until the coil 23 is completely filled, and the full refrigerative effect is resumed.

Referring now to Figure 2, the compressor is indicated at 51 and the motor at 52 and the driving belt at 53. The compressed refrigerant leaves by the high pressure line 54 which delivers it to a condenser 55 in which it is liquefied. The liquefied refrigerant flows from the bottom of the condenser 55 to a float trap 56 connected top and bottom to a suction trap 61. The float 57 in the trap 56 controls the valve 58 so as to preserve a constant level of liquid refrigerant in the trap 61.

The suction line 62 leads from the top of the trap 61 to the suction of the compressor. Leading from the bottom of the trap 61 is a downwardly extending liquid line 59. This is connected to the lower ends of three evaporator coils 63, 63a and 63b. The upper end of each of these coils is connected to a vapor line 60, but each such connection is controlled by a hand operated stop valve 66, 66a or 66b as the case may be, and by an automatic control valve 67, 67a or 67b. Each of the valves just mentioned is controlled by a corresponding progressive thermostat unit 68, 68a or 68b. The stop valves 66, 66a and 66b are used merely to shut down the corresponding coil for an indefinite period. The valves 67, 67a, etc. are progressively opened and closed by their corresponding thermostatic units 68 to control the vapor pressure in the coil and thus to displace the liquid refrigerant from the coil in varying degrees. When the coil is full of liquid the maximum refrigerative effect is secured. When it is

empty, the refrigerative effect is virtually suspended and in the intermediate cases the refrigerative effect varies according to the proportion of coil which is liquid filled.

It is obvious that a thermostatic switch similar to the thermostatic switch 36 may be mounted on any floor, preferably that having the severest and most sustained refrigerative load, and might be arranged to start and stop the motor 52 in a manner identical with that described with reference to Fig. 1.

The use of a combined liquid and vapor line such as the line 19 of Fig. 1 is useful and is an important feature of the present invention, particularly in conjunction with refrigerative evaporators having two connections to that line, the evaporators being located below the line so as to fill with liquid by gravity flow therefrom.

The arrangement has peculiar advantages in defrosting. If either the valve 26 or the valve 27, for example, be completely closed, the liquid refrigerant in the coil, such as coil 23, is completely expelled in a relatively short time. As a result the coil spontaneously defrosts itself. Such defrosting would not occur if the liquid refrigerant remained in the coil.

The system is of great practical utility where a number of evaporators must be closely regulated each independently of the others. One installation which has demonstrated great utility is that made in small butcher shops where there is a relatively large butcher box or refrigerator, whose unit is subjected to a relatively light refrigerative load, and where there is also in the same system a refrigerated display case, which, because of frequent opening, is subjected to a heavy and sustained refrigerative load. In such cases the evaporator unit in the butcher box is equipped with a control valve such as the valve 26 or 27, it being preferred to use an automatic valve such as the valve 27. Such a unit may or may not be used in the display case, although its use is preferred, but in any event the thermostatic control 36 is put in the display case, thus ensuring refrigeration to that case at all times when its temperature tends to rise above the desired value. The automatic valve controlling the butcher box coil will ensure the maintenance of the proper temperature in the butcher box.

Various other practical modifications involving similar principles will readily suggest themselves, and need not be discussed in detail. The use of a progressive thermostatic actuator in conjunction with a progressive valve such as the valve 27 offers a peculiarly even and gradual regulation such as has long been desired and seldom obtained in the art.

It is apparently unnecessary to illustrate and describe in detail the thermostatic

valves, of which the valve mechanism 27, 28, is typical, as these may assume various forms and are standard articles of commerce. One such known type of thermostatic valve includes a valve urged closed by a spring and urged open in opposition to the action of said spring by vapor pressure acting against a metallic bellows diaphragm. The vapor pressure is that generated by evaporation of a volatile liquid which develops the opening pressure at or about the temperature which it is desired to maintain. In refrigeration work it is common to use for this purpose one of the volatile refrigerants. However, the form of the thermostatic valve is immaterial.

The particular modifications shown in the drawing are intended to be illustrative rather than limiting, and it is understood that the invention is capable of embodiment in many different forms.

What is claimed is,—

1. The method of controlling the refrigerative action of a normally flooded evaporator, having two independent connections with a trap in which a charge of liquid refrigerant is maintained under suction pressure, and from which the evaporator is fed with liquid refrigerant by gravity flow, which consists in variably throttling one of said connections according to changes in the artificial temperature created by said evaporator, while evaporation of refrigerant is taking place in the evaporator, and thus varying the effective surface of the evaporator by a varying partial displacement of liquid refrigerant therefrom.

2. In a refrigerating system, the combination of a receptacle maintained at suction pressure and partially filled with volatile liquid refrigerant; and an evaporator arranged to fill with liquid refrigerant by gravity flow from said receptacle and having two connections therewith both below the liquid level in the receptacle.

3. In a refrigerating system, the combination of a receptacle maintained at suction pressure and partially filled with volatile liquid refrigerant; an evaporator arranged to fill with liquid refrigerant by gravity flow from said receptacle and having two connections therewith both below the liquid level in the receptacle; and a valve controlling one of said connections.

4. In a refrigerating system, the combination of a receptacle maintained at suction pressure and partially filled with volatile liquid refrigerant; an evaporator arranged to fill with liquid refrigerant by gravity flow from said receptacle and having two connections therewith both below the liquid level in the receptacle, and one of said connections being constantly open; and a valve controlling the other connection.

5. In a refrigerating system, the combination of a receptacle maintained at suction

pressure and partially filled with volatile liquid refrigerant; an evaporator arranged to fill with liquid refrigerant by gravity flow from said receptacle and having two connections therewith both below the liquid level in the receptacle, one of said connections being constantly open; a valve controlling the other connection; and a thermostatic actuator connected to open and close said valve as the artificial temperature created by said evaporator rises and falls.

6. In a refrigerating system, the combination of a receptacle maintained at suction pressure and partially filled with volatile liquid refrigerant; an evaporator arranged to fill with liquid refrigerant by gravity flow from said receptacle and having two connections therewith both below the liquid level in the receptacle, one of said connections being constantly open; a valve controlling the other connection; and a thermostatic actuator connected to open and close said valve progressively as the artificial temperature created by said evaporator rises and falls.

7. In a refrigerating system, the combination of a receptacle maintained at suction pressure and partially filled with volatile liquid refrigerant; an evaporator arranged to fill with liquid refrigerant by gravity flow from said receptacle and having two connections therewith, at least one of which is below the liquid level in the receptacle; a valve controlling the other connection; and thermodynamic means for opening and closing said valve in response to the rise and fall of the artificial temperature created by said evaporator.

8. In a refrigerating system, the combination of a receptacle maintained at suction pressure and partially filled with volatile liquid refrigerant; an evaporator arranged to fill with liquid refrigerant by gravity flow from said receptacle and having two connections therewith, at least one of which is below the liquid level in the receptacle; a valve controlling the other connection; and thermodynamic means for progressively opening and closing said valve in response to the rise and fall of the artificial temperature created by said evaporator.

9. In a multiple refrigerating system, the combination of a receptacle maintained at suction pressure and partially filled with volatile liquid refrigerant; and a plurality of independent cooling units each including an evaporator arranged to fill with liquid refrigerant by gravity flow from said receptacle, and having two connections therewith, at least one of such connections being below the liquid level in the receptacle, a valve controlling the other connection and thermodynamic means for opening and closing said valve in response to the rise and fall of the artificial temperature created by the associated evaporator.

10. In a multiple refrigerating system, the combination of a receptacle maintained at suction pressure and partially filled with volatile liquid refrigerant; and a plurality 5 of independent cooling units each including an evaporator arranged to fill with liquid refrigerant by gravity flow from said receptacle, and having two connections therewith, at least one of such connections being below 10 the liquid level in the receptacle, a valve controlling the other connection and thermostatic means for progressively opening and closing said valve in response to the rise and fall of the artificial temperature created by 15 the associated evaporator.

11. A multiple refrigerating system comprising in combination a suction trap; a compressor whose suction is connected therewith; means for driving said compressor; a condenser to which the compressor delivers; and means controlling the delivery of liquid refrigerant from the condenser to said trap, whereby a refrigerant circuit is formed; a plurality of cooling units connected with 20 said circuit at least one of which includes an evaporator arranged to fill with liquid refrigerant by gravity flow from said trap, and having two connections therewith, at least one such connection being below the 25 liquid level in the trap, a valve controlling the other connection, and thermostatic means for opening and closing said valve in response to the rise and fall of the artificial temperature created by said evaporator; and 30 thermostatic means responsive to the artificial temperature created by one of said cooling units for starting and stopping said compressor driving means.

12. A multiple refrigerating system comprising in combination, a suction trap; a compressor whose suction is connected therewith; means for driving said compressor; a condenser to which the compressor delivers; and means controlling the delivery of liquid 45 refrigerant from the condenser to said trap, whereby a refrigerant circuit is formed; a plurality of cooling units connected with said circuit, at least one of which includes an evaporator arranged to fill with liquid refrigerant by gravity flow from said trap, and having two connections therewith, at least one such connection being below the liquid level in the trap, a valve controlling the other connection, and thermostatic means for 50 progressively opening and closing said valve in response to the rise and fall of the artificial temperature created by said evaporator; and thermostatic means responsive to the artificial temperature created by one of said cooling 55 units for starting and stopping said compressor driving means.

13. In a refrigerating system, the combination of a condenser; a combined gas and liquid refrigerant line arranged to be fed with 60 liquid from said condenser; means control-

ling the feed of liquid from the condenser to said line; a trap for intercepting liquid refrigerant, with the gas space of which said line communicates and toward which it drains; means for withdrawing gas from said trap and delivering it under higher pressure to the condenser; and at least one evaporator connected with said combined line and arranged to fill with liquid refrigerant by gravity flow therefrom.

14. In a refrigerating system, the combination of a condenser; a combined gas and liquid refrigerant line arranged to be fed with liquid from said condenser; means controlling the feed of liquid from the condenser to said line; a trap for intercepting liquid refrigerant, with the gas space of which said line communicates and toward which it drains; means for withdrawing gas from said trap and delivering it under higher pressure to the condenser; an evaporator having two connections with said combined line and arranged to fill with liquid refrigerant by gravity flow therefrom; and valve means for controlling one of said connections.

15. In a refrigerating system, the combination of a condenser; a combined gas and liquid refrigerant line arranged to be fed with liquid from said condenser; means controlling the feed of liquid from the condenser to said line; a trap for intercepting liquid refrigerant, with the gas space of which said line communicates and toward which it drains; means for withdrawing gas from said trap and delivering it under higher pressure to the condenser; an evaporator having two connections with said combined line and arranged to fill with liquid refrigerant by gravity flow therefrom; valve means for controlling one of said connections; and thermostatic means for controlling said valve means.

16. In a refrigerating system, the combination of a condenser; a combined gas and liquid refrigerant line arranged to be fed with liquid from said condenser; means controlling the feed of liquid from the condenser to said line; a trap for intercepting liquid refrigerant, with the gas space of which said line communicates and toward which it drains; means for withdrawing gas from said trap and delivering it under higher pressure to the condenser; an evaporator having two connections with said combined line and arranged to fill with liquid refrigerant by gravity flow therefrom; valve means for controlling one of said connections; and progressively acting thermostatic means for controlling said valve means.

In testimony whereof I have signed my name to this specification.

WILLIAM E. ZIEBER.
